UNITED STATES PATENT OFFICE.

HENRY SWADBA, OF BOSTON, MASSACHUSETTS.

DESIGN FOR MERCHANDISE-DISPLAY STAND.

Application filed August 30, 1922. Serial No. 3,595. Term of patent 3½ years.

To all whom it may concern:

Be it known that I, HENRY SWADBA, a subject of the Government of Czechoslovakia, residing in Boston, in the county of Suffolk and Commonwealth of Massachusetts, have invented a new, original, and ornamental Design for Merchandise-Display Stand, of which the following is a specification, reference being had to the accompanying drawing, forming a part thereof.

I claim:

The ornamental design for merchandise display stand as shown and described.

HENRY SWADBA.
